[57] CLAIM

The ornamental design for telescoping ski boat pylon for attaching tow rope, as shown and described.

DESCRIPTION

FIG. 1 is a front perspective view of telescoping ski boat pylon for attaching tow rope showing my new design;

FIG. 2 is a bottom plan view thereof;

FIG. 3 is a top plan view thereof;

FIG. 4 is a rear elevational view thereof, a portion of the pylon being broken away for ease of illustration;

FIG. 5 is a side elevational view thereof;

FIG. 6 is a front elevational view thereof;

FIG. 7 is a front perspective view thereof in extended condition;

FIG. 8 is a rear elevational view of FIG. 7;

FIG. 9 is a side elevational view of FIG. 7;

FIG. 10 is a front elevational view of FIG. 7;

FIG. 11 is a fragmentary portion of the perspective view on an enlarged scale of the area within the circled region 11 of FIG. 7;

FIG. 12 is a fragmentary portion of the rear view on an enlarged scale of the area within the circled region 12 of FIG. 8; and,

FIG. 13 is a fragmentary portion of the front view on an enlarged scale of the area within the circled region 13 of FIG. 10.

The broken line showing of a portion of a retractable pin and ring in the drawing is for illustrative purposes only and forms no part of the claimed design.
